Bart Lund INVENTOR
BY Victor J. Evans
ATTORNEY

UNITED STATES PATENT OFFICE

BART LUND, OF HAMMOND, INDIANA

FENDER CONSTRUCTION FOR VEHICLES

Application filed January 5, 1929. Serial No. 330,637.

This invention relates to certain novel improvements in fender constructions for vehicles and has for its principal object the provision of an improved construction of this character which will be effective in its functioning and economical in manufacture.

The salient object of my invention is to provide a fender which will have associated therewith a fin construction that will prevent water and the like thrown thereagainst from passing over the edges thereof to mar the appearance of the vehicle with which it is associated.

In previous fender constructions the fender was provided with a downwardly depending lip along the outer edge thereof and when water was thrown against the under surface of the fender it would tend to run to the edge of this lip and be dispersed outwardly therefrom in a substantially fan-shape manner. Portions of this water would be picked up by the air agitated by the vehicle and this water would be blown against the body of the vehicle. Inasmuch as this water carried mud and other foreign substances the appearance of the vehicle was greatly marred when this water evaporated. It is therefore the principal object of my invention to obviate the foregoing condition.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a fragmental elevational view of a preferred form of construction for my invention;

Fig. 2 is a side elevational view of the device as illustrated in Fig. 1; and

Fig. 3 is a sectional view taken substantially on the line 3—3 on Fig. 2.

In the accompanying drawing wherein I have illustrated the preferred form of construction for my invention 10 indicates the back skirt of a fender construction of conventional design which terminates in a horizontally disposed hood portion 11 that is pro-

vided, at the edge opposite that joining the skirt 10, with a downwardly depending lip 12. The hood 11 terminates at its forward end in a downwardly depending lip portion 13. The skirt and hood 11 terminate in a substantially flat portion 14 which is intended to be connected to the running board of a vehicle as is well understood in the art. The foregoing construction is of the conventional type and it is to be understood that certain modifications may be made therein to adapt the fender for use in connection with vehicles of different design without departing from the purview of my invention.

My improvement in fender construction consists in providing a plurality of fins generically indicated by 15 which are disposed on the under side of the hood 11 and which extend longitudinally thereof. The fins 15 are arranged to have the wider end portion 16 thereof disposed adjacent the lip 13 while the thinner end portions 17 terminate adjacent the relatively flat portions 14. The intermediate portions of the fins 15 are arranged to gradually decrease in height from the wider end portion 16 to the narrower end portion 17. The fins 15 are arranged to extend radially with respect to the tire with which the fender is associated.

When water and the like is splashed against the under side of the hood 10 the fins 15 serve to direct the same downwardly toward the flat portion 14 and prevent the water from passing to and accumulating along the lower edge of the lip 12. In this manner substantially all of the water will be discharged adjacent the lowermost portion of the fender which will obviously be adjacent the flat portion 14.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claim.

Having thus described my invention what

I claim as new and desire to protect by Letters Patent is:

In a fender construction including a skirt portion and a hood portion having a downwardly depending lip, a plurality of fins arranged on the under side of said hood in spaced apart relation, said fins extending from a point adjacent the forward end of said hood to a point adjacent the rear lower end thereof, said fins being tapered longitudinally thereof and being disposed with the wider end portions adjacent the forward end of said hood while the narrower end portions are disposed adjacent the rear end thereof.

10 In testimony whereof I affix my signature.

BART LUND.
